UNITED STATES PATENT OFFICE

OLIVER W. RANDOLPH, OF TOLEDO, OHIO

DESCENDING TRAY DRIER

Application filed February 18, 1929. Serial No. 341,000.

This invention relates to removing moisture from bulk material, even up to a considerable degree of coarseness for such material.

5 This invention has utility when incorporated in the progressing and moisture removal as exposed to heat and draft of hay, chopped alfalfa, vegetables, cereals, etc.

Referring to the drawings:

10 Fig. 1 is an elevation, with parts broken away, looking into the draft delivery side of the installation as adapted to the drying of coarse chopped materials or hay;

15 Fig. 2 is a view in end elevation of the device of Fig. 1, parts being broken away;

Fig. 3 is a plan view of a tray as progressed in the disclosure herein.

Housing 1 is shown as having in its upper 20 region sprocket wheels 2 mounted on bearings 3. In this housing 1, there are below these sprocket wheels 2, sprocket wheels 4 mounted in bearings 5. About these sprocket wheels 2, 4, extend endless chains 6 carrying flights 7. These flights as moving in the downward reaches are located at corners of rectangular trays 8, serving to sustain such trays with their foraminous or wire cloth bottoms 9 in superposed relation. Supply means 25 as pneumatic stacker delivery spout 10 may discharge say chopped hay into hopper 11 having discharge gate 12 controllable by handle 13. The manual control of the delivery of the material from this hopper 11 into upper- 30 most tray 8 may be one wherein the material is spread as a layer more or less uniformly over the bottom 9 in filling the tray.

As the tray is filled, the endless belt conveyors may be released as by depressing brake bar 14 against the resistance of spring 15. This is conveniently definitely determined as to arc of movement in the withdrawing of dog 16 from seat 17, thereby determining a definite descent travel for the newly charged tray.

In the operation of the device herein, as draft treatment say for the removal of moisture, warm air duct 18 say from the furnace 45 may have power driven fan 19 therein for distributing the heated gases into ducts 20, 21,

22. In practice, there may be a ratio of control between these ducts as determined by dampers 23. Furthermore, the temperature may be further controlled as by heating coils 24 in the ducts so that a ratio of temperature 55 as desired may be adjusted for the gas as in the different ducts or other condition established.

These hot air supply ducts 20, 21, 22, extend to the housing 1 at openings 25, alternately 60 between trays 8. The discharge from the duct 20 is to the underside of this newly charged tray as brought to the first stage of operation in the housing 1. Draft from this tray accordingly moves upward through the 65 foraminous bottom and the layer of material in this upper first tray in the housing, while downward into the material as on the tray therebelow. This delivery of the hot gases into the housing passes through one tray up- 70 ward and another tray downward for flow off of the gas by outlets 26, 27, 28, 29, intermediate outlets being controllable by dampers 30. Accordingly, the effective draft may be adjusted not only by the intake dampers 23, but 75 by these discharge dampers 30.

As the top tray is fed down into this first position of treatment, a bottom tray is withdrawn by the lowering action, in that the flights 7 pass clear thereof to deposit the 80 lowermost tray on inclined roller track 31 where trunnions 32 may be engaged by bail 33 and hoist line 34 operated by motor 35 as carried by car 36 movable on overhead track 37. As thus connected, the bail balances the 85 tray 8 as removed from the housing so that at this discharge station a dumping of the draft treated material may occur as the tray is lifted from the roller track 31. The lifting action brings the tray emptied upward and 90 then, with the car 36 moving along the track 37, locates such car at the region of the hopper 11 for recharging in this closed circuit for the trays in this drying installation.

The distribution of the material as to bed- 95 ding in the trays in forming the layers may be uniform throughout or vary according to conditions found for bringing about the more uniform treatment under the draft and material conditions at hand.

It is to be noted in this step by step downward progress the only power required is that for the hoisting of the trays, the gravity of the loaded trays serving as the step by step descent control as manually released. The trays as coming to the several stations in the descent have first upward draft then downward draft therethrough. The take-off gases say as moisture laden are thus directly removed independently of re-contaminating any treated portion of the material. In some operations the products of combustion as well as additional supply of heated gases from the furnace may be used as high temperature treating medium hereunder.

15 The flights 7 are held in approximately horizontal position by evener means herein shown as bevel gears 38 fixed with the sprocket wheels 2. These bevel gears 38 are in mesh with bevel pinions 39 on common shaft 40 between the endless belts or sprocket chains 6. On one side of the housing 1 upon this shaft 40 is brake wheel 41 having manually controllable brake means 42 so that in any special desired lowering this may be effective when the brake 14 is out of holding relation. Additionally, for shifting or special moving in the event the equipment is clogged, hand wheel 43 may be operated.

30 As the more moist trays are at the top and the natural direction for hot gases is more readily upward, the greater intensity of heat at the more moist region is thus in the natural position therefor, while as the material becomes drier in the lower stages and accordingly may be more combustible, the lower temperature gases as normally supplied below, thereby automatically reduce ignition hazards.

35 What is claimed and it is desired to secure by United States Letters Patent is:

1. Apparatus for treating material comprising a column, trays spaced apart in said column, a plurality of draft entrance ways along said column between successive independent pairs of trays, each intermediate draft entrance way having upward and downward draft communication therefrom through two trays in said column, draft discharge ways from the column from between pairs of trays and alternating with said draft entrance ways, and tray actuating means for shifting the trays along the column relatively to said draft ways, said column and ways coacting for draft control flow transversely into the column at one side of a tray and out of the column at the other side of such tray, and reversing said control at a succeeding position of said tray.

40 2. Apparatus for treating material comprising a column, trays spaced apart in said column, a plurality of draft entrance ways along said column between successive independent pairs of trays, each intermediate draft entrance way having upward and

downward draft communication therefrom through two trays in said column, draft discharge ways from the column from between pairs of trays and alternating with said draft entrance ways, and successive step actuating means for shifting the trays along the column from clear of one draft way to clear of a succeeding draft way, said column and ways coacting for draft control flow transversely into the column at one side of a tray and out of the column at the other side of such tray, and reversing said control at a succeeding position of said tray.

3. In a drying chamber forming a column, a series of trays, step by step actuating means for progressing the trays through the chamber, an intake passage for draft between a pair of trays into said chamber, said trays providing ways for two-direction air flow from the intake passage, an outlet way from between each alternate pair of trays from said chamber, and controlling means for each outlet way, said column and ways coacting for draft control flow transversely into the column at one side of a tray and out of the column at the other side of such tray, and reversing said control at a succeeding position of said tray.

4. In a drying chamber forming a column, a series of trays, mounting means for the trays in vertical pairs in the chamber, step by step actuating means for progressing the trays through the chamber, a plurality of draft intake passage ways between the different vertical pairs of said trays on one side of said chamber, and a plurality of draft outlet ways between the other alternate pairs of trays on the opposite side of said chamber, each latter pair of trays providing ways for two-direction air flow therefrom to an outlet way, said column and ways coacting for draft control flow transversely into the column at one side of a tray and out of the column at the other side of such tray, and reversing said control at a succeeding position of said tray.

5. In a drying chamber, a series of trays, mounting means for the trays in a vertical column in the chamber, step by step actuating means for progressing the trays through the column, a plurality of draft intake passage ways for discharging a drying medium between superimposed pairs of said trays, a plurality of draft outlet ways thereto in two directions from the other alternate pairs of trays on the opposite side of said chamber, and independent controlling means for each outlet way, said column and ways coacting for draft control flow transversely into the column at one side of a tray and out of the column at the other side of such tray, and reversing said control at a succeeding position of said tray.

6. Apparatus for drying material comprising material supporting means providing

- a column, step by step actuating means for the supporting means in effecting a succession of reversals in drying operation, a chamber for the supporting means, a drying supply means, duct means having connection between the chamber and the supply means coacting with the supporting means for forcing a drying medium from said supply means in an up direction through a supporting means
5
10 at one step and in a down direction through said same supporting means at a succeeding step in said succession of reversals, said forcing between the steps alternating between pairs of supporting means in effecting opposite draft direction flow from the supply through material to two supporting means, and draft discharge ways from the column alternating with the supply means.
15

In witness whereof I affix my signature.
